ABSTRACT

The invention is concerned with relieving connections formed with fine wires (e.g., of 0.08 mm diameter), of strain caused by an axial tension imposed on the wires during handling. To achieve this, the wire is wound around a portion of insulating body after connection to a tab carried by the body, and is retained in position around the body by inserting the portion in a trough-like portion formed on another insulating body. The one insulating body is provided with a socket retaining a contact member electrically connected to the tab and the other is provided with a post of conductive material which is inserted into the socket to make electrical connection to the contact member on insertion of the one body into the other body.

FIG. 8.

STRAIN RELIEVED THIN WIRE TWO PART CONNECTOR

The invention relates to an electrical connector for thin wire, typically having a diameter of the order of 0.08 mm, used in very small electrical units accessory to main circuitry, for example magnetic core assemblies of logic circuits for detachably mounting on a printed circuit board of a computer or detachable parts of micro-electromagnets of microswitches. Such connectors must be very small, for example the length of a bank of ten connectors may be as small as 1 cm, while its transverse cross-section size may be as small as 1 sq. mm. The thin wire in question has very low mechanical strength and considerable care is required in handling the wire to avoid breaking it. Extra care is required in handling connections formed of such wire and other electrical conductors, for example connections formed by soldering the wire to a conductive path of a printed circuit board, since the wire is weakened, as by deformation or fusion, in making the connection. There is thus a need to relieve strain imposed on such a connection by an axial pull on the thin wire.

The invention provides an electrical connector for thin wire comprising first and second interengageable elongate insulating blocks, the first block being of trough-like transverse cross-section and having a series of posts of conductive material extending through, and outstanding from, opposite faces of the base of the trough at intervals along its length, the blocks being engageable by insertion of the second block into the trough of the first block in a free fit; the second block being formed at corresponding intervals along its lower side with a series of post-receiving sockets and having a corresponding number of tabs of conductive material upstanding from its upper side, each socket retaining a contact member electrically connected to an individual tab and arranged to effect electrical connection to a post on insertion of the second block, the arrangement being such that on engagement of the blocks a fine wire electrically connected at one end to the tab and passed transversely around the second block with its free end extending away from the upper side of the second block will be retained located around the block thereby to relieve the connection of tension forces applied to the free end of the wire.

The invention will be described by way of example with reference to the accompanying drawings, in which:

FIG. 1 is a perspective view of part of a one block having one contact to which an end of a wire has been soldered;

FIG. 2 is a perspective view of the contact of FIG. 1 integral with a carrier strip;

FIG. 3 is a perspective view of part of a second block;

FIG. 4 is an underplan view of the block of FIG. 1;

FIG. 5 is a longitudinal sectional view along line V—V of FIG. 4;

FIG. 6 is a cross-sectional view along line VI—VI of FIG. 4;

FIG. 7 is a cross-sectional view along line VII—VII of FIG. 4; and

FIG. 8 is a cross-sectional view along line VIII—VIII of FIG. 4.

One block 1 of FIGS. 1 and 6 to 8 comprises an elongate molding of insulating material having a top wall 2, a bottom wall 3 and opposite side walls 4, 5. Contact-receiving cavities 6 are spaced apart longitudinally of

the block and each opens at the top and bottom walls. The side wall 5 has a series of dead-ended slots 7 each extending upwardly a short distance from the lower end of the wall in transverse alignment with a cavity 6 and a slot 8 extends through the height of the side wall 4 parallel to each slot 7. On one side the slot 8, best seen in FIG. 6, extends longitudinally of the block a slight distance towards an adjacent cavity 6 and at the other side a shoulder 9, FIG. 7, extends outwardly of the top of the slot. Wire-receiving grooves 10 of V-section extend through the height of the side wall 5 between adjacent slots 7 and each communicate with another such groove 11 which extends transversely of the bottom wall 3 and opens in the respective wider slot 8 in the side wall 4. As can be seen in FIG. 8, the groove 10 and the floor of the slot 8 are curved. An L-shaped latch 12 extends laterally outwardly from the top wall 2 adjacent the upper end of each groove 10 and has a retaining arm 13 adjacent the upper mouth of the groove. Each slot 7 communicates with the lower portion of the respective slot 8 transversely of the block 1 through a passageway 14. The wall of the passageway 14 remote from the respective groove 10 is generally flat but the lower edge is inclined outwardly at 15, as best seen in FIG. 5. The opposite wall of the passageway 14 has a cavity opening in the top wall 2, the cavity having three straight sides 16 and a floor defining a ledge 17, best seen in FIG. 8.

Each cavity 6 has a contact 18, best seen in FIG. 2. The contact is formed with others, not shown, in strip form of resilient metal, for example phosphor bronze, and comprises a terminal post 19 having at its upper end a V-slot 20 for solder connection to a thin wire. The lower end of the post 19 has an arch-shaped hole 21 and a lateral extension 22 which has opposite lateral extensions 23, 24 adjacent its free end 25. As shown, the upper extension 23 comprises a spring blade which is bent upon itself so that the blade free end 26 of the extension 23 is in spaced relation from the body of the blade. The lower extension 24 is bent so that the free end 27 integral with a carrier strip is directed towards the plane of the extension 22. In another construction, not shown, the lower extension 22 has the spring blade. The lateral extension 22 is bent generally normal to the plane of the post 19 at 28, as shown.

The spring blade of each contact 18 is received in a respective cavity 6 by reception of the lateral extension 22 in the respective passageway 14. As the extension 22 is moved inwardly of the passageway 14 the spring blade 23 is compressed inwardly until it reaches a wall 16 when it springs out so that the free end 26 engages the ledge 17, as seen in FIG. 5. In this condition the lower portion of the post 19 of the contact 18 is received in the slot 8 with the upper portion standing proud of the block 1, and the arch-shaped hole 21 overlies the adjacent end of the groove 11. The spring blade of the contact 18 is retained in the cavity 6 by abutment of the post 19 and the base of the slot 4 which prevents further movement of the extension 22 longitudinally inwardly of the passageway 14, the opposite sides 17 and the sides of the spring blade 23 which prevent movement in the reverse direction and the shoulder 9 which prevents tilting movement of the post 19.

The one block 1 having contacts 18 is received in a channel-shaped second block 29 of the FIG. 3, having a base 30 and opposite side walls 31, 32. The base 30 contains posts 33 received in the through-holes, not

shown, having end portions projecting below the base for reception in through-holes 34 in a printed circuit board 35, conveniently associated with a computer. One side wall 31, has depressions 36 extending the height of the walls and spaced apart the distance separating adjacent posts 19 of the one block 1. The upper edges 37 of the depressions 36 are chamfered, as shown, and the intervening wall parts 38 are smooth.

In use, an end of a thin self-soldering enamelled wire 39 of FIG. 1, for example one having a diameter of the order of 0.08 mm is received in the slot 20 of a respective post 19 and then passed down the outside of the post 19 into the grooves 11 and 10 and then upwardly away from the side wall 5 of the one block 1. The wire 39 is held in the groove 10 by the latch 12. The end of the wire 39 is soldered to the post 19. Similar connections are made to other posts. The second block 29 is located on the printed circuit board 35 by reception of the lower portion of terminal posts 33 in respective holes 34 of the board and the one block 1 is then inserted into the second block 29 with the shoulders 9 of the block 1 received in the depressions 36 and the posts 19 abutted against the wall parts 38 with the wire 39 wedged therebetween. As can be seen in FIG. 8, the soldered joint is strain relieved because of the friction engagement of the wire 39 with the posts 19 and the wall 33 and with the walls of the grooves 11 and 10. The upper portion of the posts 33 of the block 29 are received in the cavities 6 and compress the spring blades 23 which act as beam springs being trapped at the root integral with the lateral extension 22 and 25 and at the free end 26 in abutment with the wall 16. In this way electrical connection is established between the posts 19 and conductive paths of the printed circuit board.

The one block 1 may be separated from the second block 29, using a tool having jaw parts adapted to engage end shoulders 40, FIG. 5. The contacts may be changed by desoldering the wire 39 from the respective post 19 which may then be separated from the respective cavity 6 by urging the free end 26 away from the ledge 17 using a screwdriver blade inserted in the cavity from the top wall 2.

In another arrangement, not shown, the terminal post 19 is smaller than the slot 8 longitudinally of the block and a wire 39 passed through the arch-shaped hole 21 is passed up the post at an angle to the vertical plane. The post may have shoulders adapted to abut the upper surface of the one block, and the spring blade may be formed on the lower extension 22.

We claim:

1. An electrical connector for thin wire comprising first and second interengageable elongate insulating blocks, the first block being of trough-like transverse cross-section and having a series of posts of conductive material extending through and outstanding from opposite faces of the base of the trough at intervals along its length, the blocks being engageable by insertion of the second block into the trough of the first block in a free fit; the second block being formed at corresponding intervals along its lower side with a series of post-receiving sockets and having a corresponding number of tabs of conductive material upstanding from its upper side, each socket retaining a contact member electrically connected to an individual tab and arranged to effect electrical connection to a post on insertion of the second block, the second block having first and second opposed sidewalls and a bottom, the tabs extending upwardly along the first sidewall, wire guiding grooves disposed in the bottom and second sidewall of the second block, the grooves being aligned with the tabs, the arrangement being such that on engagement of the blocks the tabs lie closely adjacent a side of the trough of the first block, and a fine wire electrically connected at one end to the tab and passed between a tab and the adjacent side of the trough and transversely around the second block in the wire guiding grooves with its free end extending away from the upper side of the second block will be retained located around the block thereby to relieve the connection of tension forces applied to the free end of the wire.
- 10 2. An electrical connector according to claim 1, wherein the contact members and tabs are each integrally formed from a sheet metal blank and each contact member has a contact portion comprising a resiliently flexible blade.
- 15 3. An electrical connector according to claim 2, wherein each contact member is insertable into its socket and includes a resiliently flexible locking tongue which is flexed during such insertion and snaps into engagement with an abutment surface formed in the block to lock the member in the socket.
- 20 4. An electrical connector according to claim 3, wherein the locking tongue is constituted by an extension of the blade.
- 25 5. An electrical connector according to claim 4 wherein a hook portion is formed adjacent the wire guiding groove disposed in the second sidewall of the second block and at the upper end thereof to retain the wires in the grooves.
